United States Patent Office.

WILLIAM F. JESSUP, OF SHORTSVILLE, NEW YORK.

Letters Patent No. 86,408, dated February 2, 1869.

IMPROVEMENT IN SEEDING-MACHINE.

The Schedule referred to in these Letters Patent and making part of the same.

To all whom it may concern:

Be it known that I, WILLIAM F. JESSUP, of Shortsville, in the State of New York, have invented a new and useful Seeding-Machine; and I do hereby declare that the following is a full, clear, and exact description thereof, reference being had to the accompanying drawing, making part of this specification, in which—

Figure 1 is side elevation, showing the sustaining-arm *f*.

Figure 2 is a vertical section.

The nature of this invention will be understood by reference to drawings and specifications.

To enable others skilled in the art to make and use my invention, I will describe its construction and operation.

A is a metal case, made in the usual form of seed-distributors of this class.

It has lugs, *y*, formed on the upper part, one in front, and the other in rear, by which it is fastened to the carrying-frame.

On top there is a frame, *B*, extending from the front to the rear, which forms a housing or cover for the disk *e*.

This frame is cast in one piece with the case, and makes a cheap arrangement, which is necessary in this class of seeding-machines.

Near the bottom of the case *A*, a lug, *c*, is formed, to which the sustaining-arm *f* is bolted.

This sustaining-arm *f* extends from the lug *c* to the shaft *b*, (that moves the disk,) and has a round hole, through which the shaft *b* passes.

The arm *f* has a projection, *g*, on each side, near the

lower end, and is hollowed out on the inside, so that, when it is screwed to the case, it has three bearing-points, one on the lug *c*, on the outside of the clamping-bolt *h*, and one at the outside of each projection *g*, which rest on the edge of the case.

This allows a slight yielding tendency to that portion of the arm, so that the upper end of the arm may, at any time, be pressed against the disk *e*, to hold it in place, by tightening the bolt *h*.

There is also fitted in the hole of case *A*, a round thimble or washer, *a*, which has a square hole, through which the driving-shaft *b* passes.

This gives a bearing to the shaft in the case, and steadies it, as the washer or thimble *a* revolves with the shaft.

The hole in the disk *e*, for the shaft *b*, is also square, which causes it to revolve with the shaft, by being rigidly attached.

What I claim as my invention, and desire to secure by Letters Patent, is—

1. The sustaining-arm *f*, when constructed and applied substantially as herein shown and described, in combination with the case *c* and disk *e*, for the purpose set forth.

2. The journal-thimble *a*, when constructed and arranged as shown, in combination with the shaft *b*, case *c*, and distributing-disk *e*, for the purposes set forth.

WM. F. JESSUP.
